his attorney.

UNITED STATES PATENT OFFICE.

ALPHEUS C. MERCER, OF WILKINSBURG BOROUGH, PENNSYLVANIA.

SNAP-FASTENER.

1,319,102.

Specification of Letters Patent. Patented Oct. 21, 1919.

Application filed April 18, 1919. Serial No. 290,917.

To all whom it may concern:

Be it known that I, ALPHEUS C. MERCER, a citizen of the United States, and residing in the borough of Wilkinsburg, in the county 5 of Allegheny and State of Pennsylvania, have invented or discovered new and useful Improvements in Snap-Fasteners, of which the following is a specification.

My invention consists in a new and improved snap fastener intended for detachably connecting together two articles or portions of the same article.

Thus, my fastener may be used as a substitute for buttons and button holes in garments, the securing in place of automobile curtains, and for numerous other kindred purposes.

The object which I have in view is the provision of a new and improved device for 20 these purposes which will be efficient inexpensive and durable, and which may be quickly and easily fastened, and unfastened, but cannot accidentally become unfastened.

Generally speaking, my invention is of 25 the following construction. I provide two coacting elements, a stud plate and a socket plate, which are sewed or otherwise attached to the portions of the garment to be connected together. The stud plate has projecting from its exposed face a stud with an 30 enlarged head and a restricted neck, while the socket plate is provided with a facial depression of sufficient depth to accommodate the stud. The outer end wall of said 35 depression is preferably an incline down which the stud travels while the inner end wall is more abrupt and is provided at its bottom with an opening of sufficient size to permit the head of the stud to pass through 40 to the rear side of the socket plate. A slot of sufficient width to accommodate the restricted neck of the stud, extends from said opening up the inner wall of the depression and then across the plate and preferably 45 past the center of the same. Thus an angle is formed in said slot where the inner end wall of the depression joins the flat body of the socket plate. A spring is mounted on the rear of the socket plate having a straight 50 portion disposed diametrically of the plate which, when unbowed, lies substantially flat against the plate, the inclined wall of the depression being slotted to provide clearance for the spring which also extends through 55 the slot above referred to. The center of the spring preferably coincides with or is aligned with the angle in said first mentioned slot.

I also show a new and improved form of spring and means for mounting the same upon the socket plate.

Other novel features of construction and arrangement of parts will appear from the following description.

In the accompanying drawings, which are merely intended to illustrate the principles 60 of my invention without limiting the scope of the same to the construction shown, Figure 1 is a diametric section showing the two elements of the fastener mutually engaged; Fig. 2 is a similar view of the socket plate; Fig. 3 is a rear face view of the socket plate; Fig. 4 is a similar view with the spring omitted; Fig. 5 is a front face view of the stud plate, and Fig. 6 shows the preferred 70 form of spring.

The following is a detailed description of 75 the invention.

A and B respectively represent the stud plate and the socket plate, which may be conveniently stamped from sheet metal. Their 80 perimetral edges are preferably curved rearwardly and inwardly to form a finished edge, and to strengthen and protect the plates. The plates are preferably provided with slots or holes 1 for sewing or otherwise 85 attaching the plates on garments. I have shown the plates as circular, but it will be understood that any desired shape may be adopted.

The stud plate A is provided on its outer 90 face with a stud 2 having an enlarged head and a restricted neck. I prefer to place this stud eccentrically of the plate, as shown.

The socket plate B is provided at one side 95 of its center with a depression 3 of sufficient depth to receive the stud 2, said depression being preferably disposed radially of the plate B with its outer wall in the form of an incline while its inner end wall is more abrupt, as shown. The bottom of the inner 100 end wall is provided with an opening 4 of sufficient size to permit the head of the stud to pass through the rear side of the plate B. 5 is a slot which extends from the opening 4 up the inner end wall of the depression 3 105 and then across the flat body of the plate, preferably past the center of the plate, so that when the plates are interengaged and the neck of the stud 2 occupies the inner end of the slot 5, the perimeters of the two plates 110 register, as shown in Fig. 1. The angle in the slot 5 at the top of the inner end wall of the recess 3 forms a pair of shoulders. 6 is a slot extending down the inclined outer

wall of the depression to the opening 4. The depression 3 is of proper width to permit the passage of the head of the stud 2 down the incline to the opening 4.

5 C is a spring, made of resilient wire and having a straight portion 7 which is disposed diametrically against the rear face of the plate B extending, when not bowed rearwardly, through the slots 5 and 6. I 10 prefer to form said spring in substantially an S-shape, having the straight central portion 7 and the nearly semi-circular ends 8 which may occupy the curled in perimeter of the plate B, thus mounting the spring in 15 place. I prefer also to form integral tongues 9 on the plate B, as shown in Fig. 4, which, when the spring C is installed may be bent to form loosely fitting slide bearings 9a, Fig. 3, for the ends of the portion 7 of the 20 spring.

The head of the stud 2 is provided with a diametric groove 10 which fits over the wire spring, thus preventing the stud slipping off the spring to one side.

25 The center of the spring 7 should register with the shoulders in the slot 5, so that when the spring is bowed rearwardly away from the plate B, the greatest flex will be at that point and the spring will form inclines from 30 both ends to that point.

The use of my improved fastener is as follows.

When it is desired to snap the two plates together, the plates A and B are pressed together face to face and one moves laterally 35 in relation to the other, causing the stud 2 to travel down the incline, riding by means of its groove 10 on the wire 7, and through the opening 4 to the rear of the plate B, the 40 neck of the stud entering and traveling along the slot 5. The stud bows the spring away from the plate B, thus forming of such spring an incline down which the stud slides through the opening 4. As the neck of the 45 stud passes the shoulders in the slot 5, the head of the stud passes the center of the spring and starts the ascent of the other incline in the spring, so that when the neck of the stud reaches the inner end of the slot 50 5 and the pressure between the plates is relieved, the stud is forced by the spring up behind the shoulders in the slot 5. The slot 5 is of sufficient length to permit 55 the head of the stud to seat up behind said shoulders and against the rear face of the plate B. To release the fastener the plates A and B are again pressed together so that the stud once more bows the spring until the head of the stud passes to the rear 60 of the shoulders and by a lateral movement of the plate A is caused to pass out through the opening 4. The exit of the stud through said opening is facilitated in that it is again traveling up an incline in the spring toward 65 the exposed face of the plate B. Thus the

action of the spring is to facilitate both the engagement and disengagement of the fastener but accidental disengagement of the fastener is clearly impossible, as the spring C must be bowed and the plates shifted laterally, a compound movement which could not accidentally occur.

It is evident that my fastener is positive in its action, proof against accidental disengagement, yet convenient and of durable 75 and substantial construction.

What I desire to claim is:—

1. A fastener of the character described which consists in a stud plate and a socket plate, the stud plate being provided with a 80 projecting stud having an enlarged head and a restricted neck and the socket plate being provided with a facial depression having an opening at one end of sufficient size to permit the passage of the head of the 85 stud to the rear of said stud plate and a slot, of sufficient size to permit the passage of the neck of the stud, leading from said opening up the wall of said depression and along the body of the plate, thus forming angular 90 shoulders in the wall of said slot, and a spring mounted diametrically on the rear face of said socket plate and adapted to bear on the head of said stud, whereby when said plates are compressed together said stud 95 enters said depression and bows said spring whereupon the head of said stud rides along said spring through said opening and is forced up behind said shoulders, and when said fastener is to be disengaged the plates 100 are again compressed together, bowing said spring and permitting said stud to pass out from behind said shoulders through said opening.

2. A fastener of the character described 105 which consists in a stud plate and a socket plate, the stud plate being provided with a projecting stud having an enlarged head and a restricted neck and the socket plate being provided with a facial depression having an 110 opening at one end of sufficient size to permit the passage of the head of the stud to the rear of said stud plate and a slot, of sufficient size to permit the passage of the neck of the stud, leading from said opening 115 up the wall of said depression and along the body of the plate, thus forming angular shoulders in the wall of said slot, and a spring mounted diametrically on the rear face of said socket plate and adapted to bear 120 on the head of said stud, whereby when said plates are compressed together said stud enters said depression and bows said spring whereupon the head of said stud rides along said spring through said opening and is forced up behind said shoulders, and when said fastener is to be disengaged the plates 125 are again compressed together, bowing said spring and permitting said stud to pass out from behind said shoulders through said 130

opening, the head of said stud being grooved to engage and slide along said spring.

3. A fastener of the character described which consists in a stud plate and a socket plate, the stud plate being provided with a projecting stud having an enlarged head and a restricted neck and the socket plate being provided with a facial depression having an opening at one end of sufficient size 5 to permit the passage of the head of the stud to the rear of said stud plate and a slot, of sufficient size to permit the passage of the neck of the stud, leading from said opening up the wall of said depression and 10 along the body of the plate; thus forming angular shoulders in the wall of said slot, and a spring mounted diametrically on the rear face of said socket plate and adapted to bear on the head of said stud, the ends of said 15 spring being bent and confined in the in-turned perimetral edge of said socket plate, whereby when said plates are compressed together, said stud enters said depression and bows said spring whereupon the head of said 20 stud rides along said spring through said opening and is forced up behind said shoulders, and when said fastener is to be disengaged the plates are again compressed together, bowing said spring and permitting 25 said stud to pass out from behind said shoulders through said opening.

4. A fastener of the character described which consists in a stud plate and a socket plate, the stud plate being provided with a 30 projecting stud having an enlarged head and a restricted neck and the socket plate being provided with a facial depression having an opening at one end of sufficient size to permit the passage of the head of the stud to 35 the rear of said stud plate and a slot, of sufficient size to permit the passage of the neck of the stud, leading from said opening up the wall of said depression and along the body of the plate, thus forming angular 40 shoulders in the wall of said slot, and a spring mounted diametrically on the rear face of said socket plate and adapted to bear on the head of said stud, the ends of said 45 spring being bent and confined in the in-turned perimetral edge of said socket plate, whereby when said plates are compressed together said stud enters said depression and bows said spring whereupon the head of said stud rides along said spring through said 50 opening and is forced up behind said shoulders, and when said fastener is to be disengaged the plates are again compressed together, bowing said spring and permitting 55 said stud to pass out from behind said shoulders through said opening, the head of said stud being grooved to engage and slide along 60 said spring.

5. A fastener of the character described which consists in a stud plate and a socket plate, the stud plate being provided with a projecting stud having an enlarged head and a restricted neck and the socket plate being provided with a facial depression having an opening at one end of sufficient size to permit the passage of the head of the stud to the rear of said stud plate and a slot, of sufficient size to permit the passage of the neck of the stud, leading from said opening up the wall of said depression and along the body of the plate, thus forming angular shoulders in the wall of said slot, and a spring mounted diametrically on the rear face of said socket plate and adapted to bear on the head of said stud, the center of said spring registering with said shoulders, whereby when said plates are compressed together said stud enters said depression and bows said spring whereupon the head of said stud rides along said spring through said opening and is forced up behind said shoulders, and when said fastener is to be disengaged the plates are again compressed together, bowing said spring and permitting said stud to pass out from behind said shoulders through said opening.

6. A fastener of the character described which consists in a stud plate and a socket plate, the stud plate being provided with a projecting stud having an enlarged head and a restricted neck and the socket plate being provided with a facial depression having an opening at one end of sufficient size to permit the passage of the head of the stud to the rear of said stud plate and a slot, of sufficient size to permit the passage of the neck of the stud, leading from said opening up the wall of said depression and along the body of the plate, thus forming angular shoulders in the wall of said slot, and a spring mounted diametrically on the rear face of said socket plate and adapted to bear on the head of said stud, the center of said spring registering with said shoulders, whereby when said plates are compressed together said stud enters said depression and bows said spring whereupon the head of said stud rides along said spring through said opening and is forced up behind said shoulders, and when said fastener is to be disengaged the plates are again compressed together, bowing said spring and permitting said stud to pass out from behind said shoulders through said opening, the head of said stud being grooved to engage and slide along said spring.

Signed at Pittsburgh, Pa., this 14th day of April, 1919.

ALPHEUS C. MERCER.
